UNITED STATES PATENT OFFICE.

WILLIAM F. HOSFORD, OF WEST CHICAGO, ILLINOIS, ASSIGNOR TO WESTERN ELECTRIC COMPANY, OF NEW YORK, N. Y., A CORPORATION OF ILLINOIS.

COIN-COLLECTOR.

1,076,285.

Specification of Letters Patent. Patented Oct. 21, 1913.

Application filed July 30, 1912. Serial No. 712,327.

To all whom it may concern:

Be it known that I, WILLIAM F. Hosford, a citizen of the United States, residing at West Chicago, in the county of DuPage and State of Illinois, have invented a certain new and useful Improvement in Coin-Collectors, of which the following is a full, clear, concise, and exact description.

This invention relates to coin collectors and is particularly adapted for use in connection with telephone systems, although its use is not exclusively limited to this field of operation.

The general object of this invention is to provide a new and improved form of coin mechanism for a coin collector which will deposit or refund the coin, and which is simple in construction and efficient and reliable in operation.

The invention will be fully understood from the following description taken in connection with the accompanying drawings in which the invention is shown in its preferred form.

In the drawings.—Figure 1 is a side elevation of the mechanism with the outer wall of the coin chute removed, the dotted lines indicating the walls of the coin runways carried by the outer wall of the chute; Fig. 2 is a side elevation of the mechanism comprising this invention with both walls of the coin chute removed; and Fig. 3 is a perspective view of the arresting, circuit closing, and coin directing mechanism.

To the back plate 5 is secured a coin chute 6 which consists of the usual coin receptacle 7, zig-zag channel 8, by-path 9, deposit channel 10 and refund channel 11 separated by a partition 12 carried by the outer wall of the coin chute, and refund cup 13. The cash box is located behind and below the deposit channel 10 and is not shown in detail in any of the figures, since it forms no part of this invention and its various forms are well known in the art. The coin chute, cash box and the mechanisms hereinafter described are inclosed in a protecting housing, preferably of iron, fastened to the back plate 5.

A polarized electromagnet is firmly secured to the coin chute 6 by means of screws 14, 15 and 16 and comprises coils 17 and 18 and an armature 19. The armature 19 is pivotally supported between the pointed

screws 25 and 26 and is adapted to be turned in either direction about its axis, depending upon the direction of current through the coils 17 and 18. A frame member 27 is likewise pivotally supported by the screws 25 and 26 and is provided with rearwardly projecting lugs 28 and 29. The frame member 27 is so located with respect to the armature 19 that the lug 28 or 29 is struck thereby after the armature has rotated slightly in one direction or the other. During the remainder of its movement, the armature carries with it the frame 27. This construction allows the armature 19 to gain some momentum before picking up its load and makes the mechanism positive in its operation. This arrangement is, however, no part of the present invention.

Firmly secured to the frame member 27, is a downwardly projecting arm or lever 30. This arm 30 carries a removable support for arresting the coin in its downward movement and a directing mechanism. The support consists of a forwardly projecting member or slide 31 which projects through the rear wall of the chute into the coin runway. The slide 31 is pivotally supported and carried by the lever 30 through the agency of a pin 32, and is given a forward or backward movement, depending upon the direction of motion of the armature. At the outer end of the slide 31 is a curved projection 33 which normally lies in the coin runway, and against which the coin rests. If the armature is so tilted that the right end thereof moves toward the front, the slide 31 is pushed outwardly thereby moving the projection 33 out of the runway and allowing a coin to pass down behind the said projection. If on the other hand, the armature is actuated so that the right end thereof moves in a rearwardly direction, the slide 31 is pulled from the chute allowing the coin to drop down in front of the projection 33. On one side of the axial plane of the movable armature, the lever 30 carries the forwardly projecting pin 35 normally extending across the chute. On the other side of the axial plane of the armature, the lever 30 carries the forwardly projecting pin 36 likewise normally extending across the coin chute. When the armature is actuated so that the right end thereof moves in a forward direction, the pin 36 is

forced farther within the chute to guard the deposit channel 10, and the pin 35 is completely withdrawn from the chute thereby permitting the released coin to be deflected, 5 by the directing pin 36, to the left of the partition 12 into the refund channel 11 and thence to the refund cup 13. If, on the other hand, the armature is rotated so that the right end thereof moves in a rearward 10 direction, the pin 35 moves into the chute to guard the refund channel, while the pin 36 is completely withdrawn from the chute, permitting the released coin to be deflected, by the directing pin 35, to the right of the 15 partition 12 into the deposit channel 10 and thence to the cash box.

In a horizontal line with the projection 33 of the slide 31 is a lever 37 pivoted at 38. The projection 33 and the lever 37 are so 20 situated and spaced that a coin of the proper size moving down the zig-zag channel 8 from the coin receptacle 7 lodges between them and is held in this position until released by the operator energizing the coils 25 17 and 18. The weight of the coin rotates the lever 37 about its axis 38 and two contact springs 39 and 40 insulated from the frame and from each other, lie in such a position that the spring 39 is struck by the 30 lever 37 in its movement about the pivot 38 and is moved into engagement with the spring 40. The lever 37 may be insulated from the springs by an insulating pin 41 carried thereby. The springs 39 and 40 constitute a normally open contact in the signal 35 circuit; and it is evident that with this construction the signal circuit does not pass through the coin or through the frame of the mechanism, and that this circuit is consequently positively and dependably controlled.

The lever 30 also carries a lug 45 which projects behind the directing pin 36; and this lug 45 is provided on its top side with 45 a V-shaped slot 46 having shoulders 47 and 48 on each side thereof. The lever 37 is provided with a long laterally projecting arm 49 which is normally held in the V-shaped slot 46 by the action of gravity and 50 the retractile force of the spring 39. When the armature is rotated in either direction, and the lever 30 is thereby moved, the arm 49 rides out of the V-shaped slot 46 and rests upon either the shoulder 47 or 48 de- 55 pending upon the direction in which the armature is moved. The arm 49 is thus held in an elevated position causing the lever 37 to hold the contact springs 39 and 40 together until the armature 19 resumes 60 its normal position. Thus, the continuance of the signal, until the operator's key is released, is insured and the possible catching of a coin between the outside wall of the chute and one of the directing pins due to 65 the armature snapping back to normal po-

sition upon the release of the coin is prevented.

In case a coin of a size smaller than that which is required is deposited, it will not be held between supporting lever 37 and projecting slide 31 but will pass between these to the left of the partition 12 into the refund channel 11 and refund cup 13. If a coin is in the arrested position between the supports 31 and 37 and another coin is placed 70 in the receptacle 7 and released, it will strike the top of the arrested coin and be deflected into the by-path 9 to the refund channel 11 and refund cup 13. 75

I claim:

1. In a telephone toll mechanism, a coin chute, supports for temporarily arresting a coin therein, circuit closing contacts actuated by a coin in said temporarily arrested position, directing means projecting into 80 said chute, and an electromagnet for removing one of said supports and operating said directing means.

2. In a telephone toll mechanism, a coin chute, supports for temporarily arresting a 90 coin therein, one of said supports being removable from the chute, circuit closing means actuated by a coin in its temporarily arrested position, coin directing means projecting into said chute, and an electromagnet 95 for actuating said removable support and controlling said directing means.

3. In a telephone toll mechanism, a coin chute, circuit closing means projecting into said chute, supports for temporarily arresting a coin therein, one support being removable from the chute and the other being operable by a coin for actuating said circuit closing means, directing means for the coin distinct from said supporting means, an 100 electromagnet, and an operative connection between said electromagnet and said removable support and said directing means.

4. In a telephone toll mechanism, a coin chute; circuit closing means; supports for 110 temporarily arresting a coin in said chute, one of said supports being removable and the other being operable by a coin in its temporarily arrested position to actuate said circuit closing means; two coin directing 115 means both being removable from said chute; an electromagnet; and means operable by said electromagnet and connected to said removable support and directing means for actuating said removable support and controlling said directing means.

5. In a coin collector for a telephone, a coin chute, circuit closing means, two supports and two directing means projecting within said chute one of said supports being 125 removable from the chute and the other being operable by a coin to actuate said circuit closing means, an electromagnet, and means operable by said electromagnet and connected to said removable support and direct- 130

ing means for removing the removable support from the chute and actuating said directing means.

6. In a coin collector for a telephone, a coin chute, circuit closing means operable by a coin in said chute, supports for temporarily arresting a coin therein one of said supports being removable, means for directing the coin after the same is released by said removable support, an electromagnet, an armature therefor, and means operatively connecting said armature and said support and directing means whereby said removable support and directing means are controlled and said circuit closing means are locked in operative position.

7. In a coin collector for a telephone, a coin chute, a lever operated by a coin therein, circuit closing means operable by said lever, a removable support coöperating with said lever for arresting a coin in operative relation to said lever, directing means in said chute, an electromagnet, an armature operated thereby, and a lever operated by said armature in its movement and connected to said removable support and directing means to withdraw said removable support, operate said directing means and lock said first mentioned lever in operative relation to said circuit closing means.

8. In a coin collector for a telephone, a coin chute having two diverging channels, supports for temporarily arresting a coin above said diverging channels one of said supports being non-removable and the other removable, circuit closing means operable by a coin through the agency of said non-removable support, directing means in each

of said diverging channels, an electromagnet, an armature therefor, and means controlled by said armature and connected to said removable support and to said directing means for operating said removable support, withdrawing one of said directing means from its associated channel and locking said circuit closing means.

9. In a coin collector for a telephone, a coin chute having two diverging channels, a pivotally supported lever projecting into said chute above said diverging channels, and arranged to be actuated by a coin, a removable support projecting into said chute and coöperating with said pivoted lever for temporarily arresting a coin above said diverging channels, circuit closing means actuated by a coin in said temporarily arrested position through said pivoted lever, coin directing means projecting into each of said diverging channels, an electromagnet, an armature therefor, and a second lever actuated thereby and provided with lateral projections connected to said removable support and to said directing means and coöperating with said first mentioned lever, for releasing a coin, removing one of said directing means from its associated channel and locking said first mentioned lever in operative relation to said circuit closing means.

In witness whereof, I hereunto subscribe my name this 24th day of July A. D., 1912.

WILLIAM F. HOSFORD.
